UNITED STATES PATENT OFFICE.

JAMES BENSON, OF BELLAIRE, OHIO.

IMPROVEMENT IN SAND-PUMPS.

Specification forming part of Letters Patent No. 58,579, dated October 9, 1866.

To all whom it may concern:

Be it known that I, JAMES BENSON, of Bellaire, in the county of Belmont and State of Ohio, have invented a new and useful Improvement in Sand-Pumps; and I do hereby declare that the following is a full, clear, and exact description thereof, which will enable those skilled in the art to make and use the same, reference being had to the accompanying drawings, forming part of this specification, in which—

Figure 1 is a longitudinal section on the line α of Fig. 2. Fig. 2 is a plan showing the sucker or piston.

Similar letters of reference indicate corresponding parts.

The object of this invention is to construct a pump for removing sand, mud, and reduced rock from an oil or other deep well. The body of the pump is of such a size as to pass easily into the bore of a well. The piston-rod has a loop made in it, through which passes the bail of the pump. The length of the loop determines the stroke of the piston. When the piston is to be removed from the pump, the bail, which is hinged at one end and secured by a removable pin at the other, is swung open out of the loop, when the piston can be drawn up out of the box or body of the pump.

The letter A designates the body or box of the pump. The upper part of the pump is square to receive the piston, and the lower part has feet B to keep it from sitting too near the bottom when lowered. The upper part of the pump has on two of its sides lugs H H', to one of which is hinged a bail, I, which is connected to the other lug by a pin, J, which can be removed at pleasure. C is the lower or fixed valve of the pump. E is the piston-rod, to whose lower end is attached an ordinary bucket-valve, D, with straight sides, which, when expanded, meet the sides of the pump-box. The sides of the valve are con-

nected to the piston by straps F in the ordinary way of making such valves. The upper end of the piston-rod is formed with a loop, F', whose top and bottom form shoulders g g, which strike against the bail I in the working of the pump. The bail I is inserted in the loop when the piston-rod is drawn to its full extent upward, and is fastened to the lug H' by the pin J.

When the pump is full and it is desired to empty it, it is drawn out of the well by its bail, the piston-rod is drawn up to its full height, the pin J is taken out, the bail thrown backward out of the loop in the piston-rod, when the piston can be removed and the pump emptied.

That part of the piston-rod which contains the loop is made of metal, while the part to which the valve is fastened is of wood.

The bail holds the pump while it is lowered into a well or raised therefrom.

The piston is worked up and down by a rope fastened to its top, the shoulders g g in its loop striking against the bail, which thus limits the extent of its motion and prevents it from working out of the pump-box.

The weight of the metallic portion of the piston-rod will suffice to sink the piston in the pump after each elevation.

The pump can be made of any length or diameter to suit the well for which it is provided.

I claim as new and desire to secure by Letters Patent—

The hinged bail I, operating in combination with the linked piston-rod E of the sand-pump herein described, as and for the purpose specified.

JAMES BENSON.
